UNITED STATES PATENT OFFICE

2,608,692

COMBINED STOCKING SUPPORTER AND
BLOUSE HOLDER

Elaine Berg, Chicago, Ill.

Application November 5, 1947, Serial No. 784,154

5 Claims. (Cl. 2—323)

1

The present invention relates to supporter assemblies for supporting stockings and holding down shirts and blouses, and is particularly concerned with an improved commercial form of the supporter assembly covered by my prior application, Serial No. 729,848, filed February 20, 1947, now abandoned.

One of the objects of the invention is the provision of an improved device which is simple in construction, capable of economical manufacture, and adapted to be used not only to hold down the shirt or blouse of the wearer, but also to support the stockings.

While there are many devices on the market for use in holding down a lady's blouse, practically none of them is efficient or successful, as most of them with which I am familiar are bulky and uncomfortable; and the devices of the prior art are generally mounted on the skirt or added to the waistline, thereby increasing the size of the waistline of the wearer without securing the desired result.

Another object of the invention is the provision of an improved garment assembly, by means of which garter belts may be eliminated in the case of a lady; and in any event, the usual circulation-constricting garters, which encircle the leg, may also be eliminated.

Another object of the invention is the provision of an improved device which is adapted to hold down a blouse or shirt and to support stockings; which does not restrict the circulation of the wearer, which is comfortable to wear; and which does not restrict the movements of the wearer or add to the bulk of his or her garments, so that the stockings may be properly supported and shirt or blouse held down against creeping out of the belt, without any of the disadvantages which are present in the devices of the prior art.

Another object of the invention is the provision of an improved device of the class described, which is adapted to be sold as a unit, and which is applicable to all kinds of stockings and shirts and blouses, and which is easily attachable and detachable, so that the purchaser may wear any number of the devices which he or she pleases or which are considered necessary for effective support, and so that users may utilize the benefits of the invention at a minimum cost by cutting down on the number of units employed.

A still further object of the invention is the provision of an improved device of the class described which is more simple than the devices of the prior art, and which is more flat, so that it does not cause any substantial bulge or disfigure-

2

ment underneath the garments of the wearer, particularly at the top, where the attachment to the blouse is located, below the belt and waistline, at the lower border of the blouse, where the ordinary fasteners of the prior art would be particularly noticeable and unsuitable because of their bulging characteristics.

Another object is to reduce the number of parts, and to reduce the amount of labor in assembling them by so constructing the device that the same stitching secures a plurality of parts together at the same time, thus saving both material and labor, and reducing the cost to the purchaser.

15 Other objects and advantages of the invention will be apparent from the following description and the accompanying drawings, in which similar characters of reference indicate similar parts throughout the several views.

20 Referring to the single sheet of drawings,

Fig. 1 is a diagrammatic elevational view showing the torso of a wearer, in dotted lines, and illustrating the application of a plurality of the present devices to the support of the stockings and for the retention of a blouse of a lady;

25 Fig. 2 is a half size fragmentary elevational view of the assembly of a single unit with a blouse and stocking shown in dotted lines, using my improved fastener at both ends of the device;

30 Fig. 3 is a view similar to Fig. 2, showing a modification in which the garter fastener of the prior art is employed on the lower end of the device, as such garter fasteners can be purchased as finished units on the market; and flatness is not so important at the lower end of the device;

35 Fig. 4 is an enlarged fragmentary elevational view of my improved flat fastener, shown in unfastened condition in connection with a piece of fabric in phantom, and in dot-dash lines;

40 Fig. 5 is a sectional view, taken on the plane of the line 5—5 of Fig. 4, looking in the direction of the arrows, with the fabric omitted;

45 Fig. 6 is a fragmentary side elevational view, on a larger scale, showing the construction at the lower end of Fig. 2, which is required to provide adjustability in length of the device in this embodiment;

Fig. 7 is an enlarged plan view of the button.

Referring to Fig. 2, one of the devices embodying the invention is indicated in its entirety by the number 10; and each such device preferably consists of an elongated strip of elastic fabric 11, provided at each end with an improved securing device or fastener of my improved con-

struction, 12, 13, adapted to be secured to stockings or to a blouse, without tending to tear the fabric, and without producing any substantial bulge under the clothing of the wearer.

The elastic fabric 11 preferably consists of a multiplicity of strands of longitudinally extending rubber which are surrounded by a knit fabric which is capable of stretching longitudinally when the rubber stretches, but which also has a limit beyond which the fabric will stretch no farther. Thus the elastic member 11 may be drawn taut to a point where it will stretch no farther; but may also have the elasticity which tends to take up any looseness which may occur thereafter.

In the preferred embodiment of the invention, of Fig. 2, the two fasteners 12 and 13 are identical in construction; but are secured to the elastic strip 11 in a different way, to provide for adjustability in length of the strip 11.

For example, the assembly at the upper end, Fig. 4, Fig. 5, may include only five parts, of which the elastic strip 11 is one; and the others are the button 14, the tape loop 15 supporting the button or disc 14, the slot member 16, and the stitching 17.

The button 14 may be made of metal or non-metallic material, such as a moldable plastic; and it is preferably quite large, quite flat, and very thin. Instead of the usual four holes, the 30 button is provided with a pair of parallel apertures 18, 19, which are long enough to receive the tape 15 without wrinkling, and preferably quite narrow, being only wide enough for convenient insertion of the tape.

The tape 15 is passed successively through the slots 18, 19, entering at the back of the button, and emerging also from its back, the two ends of the tape loop being equalized and brought together. The end of the elastic strip 11 is passed 40 through the slot member 16, and folded back upon itself.

One or more lines of stitching 17 are then used to secure the end of the elastic fabric 11 into a loop 20 and to secure the tape loop 15 to the elastic fabric strip 11, with the button 14 extending in the same direction as the rigid endless loop 16 and preferably located midway of the member 16.

The slot member 16 may be made of a metal stamping or molded of a suitable initially plastic composition. This member has a slot or elongated aperture which is wide enough to pass the button 14 and its tape 15, when covered with fabric, such as the blouse 21 or stocking 22. It is also long enough to pass the fabric 21 or 22 and the button edgewise. Thus, when the button is turned to a position parallel to the slot member 16, the button spans the long sides 23, 24 of the slot member 16, toward which it is drawn by 50 the tape 15.

In order to provide for adjustability in the length of the device 10, for long or short stockings, long or short shirt tails, or for tall or short persons, the lower fastener 13 is preferably secured to the elastic strip 11 by means of an adjustable loop of elastic 25, which is formed by folding the elastic strip 11 backward upon itself at 26.

The free end 27 of this adjustable loop portion 25 may be secured to the central leg 28 of a friction slider 29, which has a pair of elongated slots for the elastic strip 11, indicated at 30, 31. The elastic strip 11 passes in at the bottom of slot 30, over leg 28, and backward through slot 31. 70

Then the elastic strip 11 passes through a slot in the rigid loop 40 and has its end secured to the central leg 28 in any suitable manner. The bends in the elastic strip 11, as it passes through the slider 29, cause the slider 29 to be held frictionally in any adjusted position.

Thus the length of the loop portion 25 of the elastic strip 11 may be adjusted by sliding the slider 29 upward or downward; and the overall 10 length of the device 10 may thus be adjusted to suit the wearer. In other embodiments of the invention the friction slider may be replaced by the standard garter adjuster 32, shown in Fig. 3, and consisting of a sheet metal body 33 embracing the elastic strip 11 and having a pivoted toothed member 34, which clamps the elastic strip 11 in various adjusted positions.

Instead of being secured directly to the elastic strip 11, the lower fastener 13 is secured to 20 an intermediate double loop member 35 (Fig. 6). This double loop member 35 is formed of a strip of tape fabric, beginning at the end 36, which extends downward and is folded back on itself at 37, forming a lower loop for a second slot member 38, similar to the slot member 16, previously described.

The tape of the double loop 35 passes through the slot member 38, and thence extends upward, past the end 36 to the point 39, where it is bent 30 downward again to form an upper loop 39. A closed chain link 40 is provided, which may comprise a pair of parallel sides joined by curved end portions for permitting the adjustment loop 25 to slide while it is being adjusted in length. Link 40 is adapted to receive the upper end 39 of the double fabric tape loop 35, which is then bent downward until its end portion 41 overlaps the portions 36 and 42 of the tape. These are then secured together by a double line of stitching 43, which also secures the button loop 15 to the double loop 35. The button loop 15 again passes through the slot member 38 and carries the button 44.

Referring to Fig. 3, this is a modification in 45 which the standard type of garter fastener is used on the bottom end.

Such a garter fastener may be assembled with parts purchased on the open market, including a base member 46, carrying a rubber covered head 47, and engageable with a wire loop 48 having a narrow end portion 49 and an enlargement 50 for passing the head 47. This type of fastener has the disadvantage that it is not flat enough to be invisible when used at the upper end; but it is not so objectionable at the lower end, where the skirts are spaced from the limbs of the wearer.

In the preferred form of the invention the flat fastener 12 or 13 is used at both ends, thus reducing the cost of the assembly and making it practically invisible under all conditions.

The operation of the device is as follows: A generous portion of the fabric of the garment to which it is to be attached is laid over the button. The button is then turned edgewise and inserted with the fabric through the slot member 16; and then the button and fabric are turned so that the button is parallel to the slot member 16. When the strip 11 and the fabric of the garment are pulled taut, the garment fabric snubs about the button and is held tightly without danger of tearing. It will be evident that the length of the device may be so adjusted that it will hold the blouse down, while holding the stockings up.

While I have illustrated a preferred embodiment of my invention, many modifications may

be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A fastener for securing a tension member to a garment to be supported, comprising a strip of fabric bent back upon itself to form a loop, and a second strip of fabric bent back upon itself to form a loop, both of said loops being secured to each other by the same line of stitching passing through both strips, a thin, flat, slot member carried by the first-mentioned loop, and a thin, flat disc carried by the second-mentioned loop, said thin, flat disc having a pair of parallel apertures for receiving said second loop, and said slot member having a slot with parallel sides spaced sufficiently to pass the disc when covered with the fabric of said garment, and said slot member having its slot provided with curved ends spaced from each other sufficiently to pass the disc when covered with the fabric.

2. A supporter assembly comprising an elongated strip of elastic fabric and a flat fastener assembly carried by one end of said fabric, said fastener assembly comprising a thin, flat disc having a pair of apertures, a strip of fabric forming a loop passing through said slots and bent to bring its ends together, and including a thin, flat, slot member having a slot with parallel sides and rounded ends secured by a loop in said end of said elastic fabric, the said loops being secured together in such position that the disc and slot member overlap each other.

3. A supporter assembly comprising a strip of fabric formed with a loop at each of its ends, said fabric being folded back upon itself and stitched together to form one of said loops, one of said loops passing through a thin, flat, rigid slot member, a second fabric strip having its ends secured together and forming a third loop and secured to one of the first-mentioned fabric loops by the same line of stitching, said third fabric loop passing through a pair of apertures of a thin, flat, circular disc, the said disc being of sufficient size to be passed through the first-mentioned slot member when the disc is arranged edgewise with respect to the slot member, but the disc spanning and engaging the sides of the slot members when the disc is parallel to the slot member.

4. In a supporter assembly for supporting stockings and holding down shirts or the like,

the combination of a strip of elastic material with a garter fastener secured to its lower end for engagement with a stocking, a thin, flat, circular disc having a pair of apertures, a strip of tape fastened through said apertures and being formed into a loop and having its ends stitched adjacent to the upper end of the elastic strip, said elastic strip also having a loop formed in its end adjacent to said disc by bending the strip upon itself and securing the overlapping parts by stitching, and said latter loop supporting a thin, flat, rigid slot member of sufficient length to pass said disc, and of sufficient width to pass said disc but of such shape that the disc will engage flatly against said rigid slot member when it has been passed through the latter and is drawn in position by its tape.

5. A supporter assembly comprising a strip of fabric formed with a loop at each of its ends, said fabric being folded back upon itself and stitched together to form said loops, one of said loops passing through a thin, flat, slot member, a second fabric strip having its ends secured together and forming a third loop and secured to one of the first-mentioned fabric loops by the same line of stitching, said third fabric loop passing through two apertures of a thin, flat, circular disc, the said disc being of sufficient size to be passed through the first-mentioned slot member when the disc is arranged edgewise with respect to the slot member, but the disc spanning and engaging the sides of the slot member when the disc is parallel to the slot member, the first-mentioned fabric strip passing through a friction slider, and a rigid, oval, closed link and having its end attached to the center bar of the friction slider to form the other of said first-mentioned loops, thus providing an adjustable loop for varying the length of said strip.
